UNITED STATES PATENT OFFICE.

CHARLES A. TATUM, OF NEW YORK, N. Y.

DESIGN FOR A WATER-BOTTLE.

SPECIFICATION forming part of Design No. 30,433, dated March 28, 1899.

Application filed February 27, 1899. Serial No. 707,119. Term of patent 7 years.

To all whom it may concern:

Be it known that I, CHARLES A. TATUM, a citizen of the United States, residing at New York city, borough of Manhattan, county and 5 State of New York, have invented and produced a new and original Design for Water-Bottles, of which the following is a specification.

My design for a hot-water bottle, which is 10 shown in the accompanying drawing, has for its leading or essential feature a trimming surrounding the body portion of the bottle of a color or tint contrasting with the color or tint of the bottle-body and having indented 15 or serrated edges.

In the drawing, A is the bottle-body, B the funnel or bottle-mouth, and a a trimming surrounding the bottle-body and of a different tint or color than the said bottle-body and having indented or serrated edges, as shown. 20

What I claim is—

The design for a water-bottle substantially as shown and described.

CHARLES A. TATUM.
